FIELD TELEPHONE SYSTEM

Frank A. Leibe, Quakertown, Pa., assignor to Federal Telephone and Radio Corporation, New York, N. Y., a corporation of Delaware

Application May 13, 1943, Serial No. 486,755

6 Claims. (Cl. 179—1)

This invention relates to telephone systems of the type in which a receiver and a transmitter at one end of a telephone line are alternately switched into operation, an arrangement especially adapted for use in field telephones. In systems of this type it is desirable that an operator who has finished transmitting and is about to switch his set from transmitting to receiving position shall notify the other operator of that fact so that the latter will know when to switch in his transmitter and commence talking. The invention is particularly intended for systems in which vacuum tube amplifiers are used at each end of the line.

The general object of this invention is to provide a novel switch-over signal that will be automatically transmitted from a set at one end of the line when the set is switched from transmitting to receiving position. A feature of the invention is the utilization of the vacuum tube amplifier circuits for this purpose.

An important object is the provision of an arrangement that will generate a switch-over signal without the use of separate signal-producing devices. This is in general accomplished by creating signal-producing oscillations in the tube circuits for a brief period at the time when the set is switched from sending to receiving position. A feature of the invention is the attainment of this object by the use of simple circuit arrangements automatically producing a brief period of oscillation whenever the set is switched over to receiving position, and which are adapted for incorporation in highly compact field sets without increasing the size of such sets.

Other objects and advantages will appear from the following description considered in connection with the accompanying drawings, in which

Fig. 1 is a simplified diagram illustrating one form of the invention, and

Fig. 2 is a similar diagram illustrating another embodiment.

Referring to Fig. 1, a handset 10 is indicated, including a receiver 11 connected by leads 12, 13 across a section of induction coil 14 with a condenser 15 in lead 12, while the transmitting microphone 16 is connected by leads 13, 17 across another section of said coil. A battery 18a in lead 17 supplies power for the transmitting microphone and push switch 18 in the same lead, which may be incorporated in the handset, serves to throw the set into and out of transmitting position.

The handset 10 is connected to transmission line 19 through a vacuum tube amplifying sys-

tem which includes a receiving amplifier tube 20 and a transmitting amplifier tube 21, together with a suitable arrangement for placing in operation tube 20 when switch 18 is open, and tube 21 when said switch is closed. In the form illustrated in Fig. 1, this is accomplished by alternately energizing the filaments of the tubes, an arrangement that is advantageous for battery operated field sets since it requires the heating of only one tube filament at a time. This switch arrangement is utilized to produce the switch-over signal, and takes advantage of the fact that if one of the filaments is disconnected when the other filament is simultaneously energized, the former filament will retain its electron-emitting temperature long enough to produce simultaneous operation of the tubes for a brief period lasting until the temperature of the cathode of the de-energized tube drops below the temperature of useful emission. By providing proper coupling between the circuits of the two tubes during this brief period of simultaneous operation, oscillations are produced which are transmitted over the line 19 to the other set.

In the form shown, the filament 22 of tube 20 is connected through line 23 and filament battery 24a to line 17, and its energizing circuit is completed through line 25 and upper contact 26 of one pole of switch 18 which is connected to line 17, said switch being of the double-pole, double-throw type. Operating grid 27 is coupled to transmission line 19 through winding 28 of transformer 29, while the anode 30 is connected to winding 31 of transformer 32 in inductive relation to winding 33 connected across the induction coil 14 and condenser 15 in the handset circuits. Tube 20 is preferably provided with a screen grid 34 connected to an appropriate source of positive potential in the usual way. With this arrangement signals coming in on line 19 are impressed through transformer 29 on tube 20, amplified, and transmitted through transformer 32 to the receiver 11.

The filament 36 of transmitter tube 21 is connected at one side through line 37 and 23 to handset line 17, and at the other side through line 38 to filament battery 24b and the lower contact 39 of the upper pole of switch 18. Operating grid 40 is connected to winding 41 of transformer 32, while anode 42 is connected to winding 43 of transformer 29. Tube 21 is advantageously provided with a screen grid 44 connected to a suitable source of positive potential. With this arrangement the waves from the circuit of microphone 16 will be impressed through transformer

32 on tube 21, amplified therein and transmitted through transformer 29 to line 19. The operation of push switch 18 will thus serve not only to shift the handset circuits between transmitting and receiving positions, but also to energize the filament of the appropriate tube and de-energize the filament of the remaining tube.

The operating grids and anodes of the tubes are suitably connected and placed at proper potentials. In the arrangement indicated negative feedback circuits are included. In the circuit connected to tube 20 the anode 38 is connected through condenser 45, resistance 46, resistance 47 and condenser 48 in parallel to line 38, the return 49 from transformer winding 28 being adjustably connected to resistance 46 to provide variable grid bias from filament battery 24b, functioning as a gain control, with the usual condenser 50 in shunt. The outer end of winding 31 is connected to a suitable grounded source of positive anode potential. The negative feedback circuit for tube 21 comprises the connection of anode 42 through condenser 51 and resistance 52 to winding 41 of transformer 32, the other end of the winding going to grid 40, the lower end of resistance 52 being connected through parallel resistances 53 and condenser 54 to line 25 and the negative side of battery 24a which provides bias potential for grid 40. The outer end of winding 43 is likewise connected to an appropriate source of positive potential. The negative sides of filament battery 24 and the sources of positive potential are of course connected in the usual manner, as by grounding to the metal frame.

With this arrangement the simultaneous operation of tubes 20 and 21 during a brief period after switch 18 is shifted will produce oscillations, due to the coupling between the circuits of the two tubes through the coils of transformers 29 and 32, which will be transmitted over line 19 and heard in the receiver of the handset at the opposite end of the line. This arrangement has the advantage of battery economy since only the filament of the tube that is in use is heated.

Another embodiment is illustrated in Fig. 2, and employs a similar arrangement of transmitter and receiver circuits, input and output transformers and double-pole switch, which are indicated by the same numerals as similar parts in Fig. 1. In this arrangement, however, the filaments 22, 36 are continuously heated by batteries 24 grounded at the negative pole in the usual way. Control grids 27 and 40 are maintained at a negative voltage sufficient to block each tube when not in operation. This voltage may be applied in any desired way, the form illustrated utilizing biasing batteries 63. The screen grids 34, 44 are connected by lines 64, 65 to the upper and lower switch contacts 26, 39 respectively, and thence through the switch to a suitable source of positive potential such as grounded battery 66. Said potential has a value appropriate to overcome the blocking bias on the control grid and to place each tube in operation when its screen grid is connected to battery 66 by switch 18.

A condenser 67 is connected between line 65 and ground, and is of appropriate capacity to maintain on screen grid 41 of the transmitter tube 21 a potential sufficient to keep said tube in operation for a brief signal period after tube 20 has been placed in operation by throwing switch 18 from transmitting to receiving position, the duration of the signal period being determined by the

rate at which the charge leaks off of the condenser. With this arrangement, since both tubes will be functioning simultaneously during said period, the coupling between the tube circuits will generate audible oscillations that will be transmitted over the line 19 to the receiver at the opposite end of the line, informing the operator at that end that the other set has been switched from transmitting to receiving position.

10 While two embodiments of the invention have been described, it will be understood that other embodiments may be employed without departing from the invention as set forth in the claims. In particular, the tubes may be placed in and out of operation by various known changes in their circuits and in particular by changing the potentials applied to various electrodes, such as 15 additional control grids.

What is claimed is:

20 1. A telephone transmitting and receiving unit comprising a transmitting system including an amplifying vacuum tube, a receiving system including an amplifying vacuum tube, switch means for placing said systems alternately in operation and means for automatically generating a switch-over signal comprising means for maintaining the transmitter system tube in operation during a signal period following actuation of the switch means to place the receiving system in operation, and coupling means connecting said systems for generating signal oscillations in the transmitter system during said period.

25 2. A transmitting and receiving unit as set forth in claim 1, in which the coupling means includes a line transformer coupled to the transmitting system tube output and to the receiving system tube input and a second transformer coupled to the receiving system tube output and to the transmitting system input, and in which said unit includes a microphone circuit in the transmitting system and a receiver circuit in the receiving system, both of said circuits being coupled to the second transformer.

30 3. A telephone transmitting and receiving unit comprising a transmitting system including an amplifying vacuum tube, a receiving system including an amplifying vacuum tube, and means for placing said systems alternately in operation and automatically generating a switch-over signal, comprising switch means for alternately energizing the filaments of said tubes, and coupling means connecting said systems for generating signal oscillations in the transmitter system throughout the period of simultaneous operation of said tubes and systems during the persistence of useful emission in the deenergized tube.

35 4. A telephone transmitting and receiving unit comprising a transmitting system including an amplifying vacuum tube, a receiving system including an amplifying vacuum tube, switch means for placing said systems alternately in operation, including means for alternately applying blocking and unblocking potentials to electrodes of said tubes, and means for automatically generating a switch-over signal comprising means for maintaining said unblocking potential on the transmitting tube electrode during a signal period following the application of said unblocking potential to the receiving tube electrode, thereby maintaining both tubes in operation during said signal period, and coupling means connecting said systems for generating signal oscillations in the transmitting system during said period.

40 5. A transmitting and receiving unit as set

forth in claim 4, in which said tubes are each provided with a screen grid and a control grid, both control grids being maintained at blocking potentials, and in which the screen grids are alternately connected to a source of unblocking potential by said switch means.

6. A transmitting and receiving unit as set forth in claim 4, in which the means for maintaining unblocking potential on the transmitting tube during a signal period includes capacitance

means in circuit between said potential applying means and said transmitting tube electrode, for maintaining an unblocking potential on said latter electrode after application of said potential thereto ceases, during the signal period in which the condenser means potential drops through leakage to the minimum unblocking potential.
